BINDING POST

Carl Orlando, Brooklyn, N. Y.

Application November 17, 1944, Serial No. 563,981

4 Claims. (Cl. 173—259)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to binding posts and more particularly to binding posts designed in one operation both to remove the insulation from a wire and to firmly grasp the conductor of the wire.

It is an object of this invention to provide a means whereby insulation may readily be removed from a wire.

It is another object of this invention to provide a means whereby the electrical conductors of a wire shall be grasped by the binding post in such a manner that it will be impossible for electrical contact to be lost due to mechanical vibration.

It is a further object of this invention to provide a means whereby an insulated electrical conductor may be attached to a binding post so that a minimum of insulation will be removed.

It is a further object of this invention to provide a means whereby the foregoing objects may be accomplished in one operation.

It is another object of this invention to provide a means of accomplishing the foregoing objects by the use of apparatus that shall be simple and inexpensive to manufacture.

Other objects and advantages of this invention will be apparent from the following description of one embodiment of my invention, read in connection with the attached drawings.

Figure 1 is an elevational view of one embodiment of my invention.

Figure 2 is a longitudinal section of the binding post of Figure 1.

Figure 3 is an exploded elevational view, partly sectioned, of said binding post.

Figure 4 is an enlarged fragmentary sectional view of the fingers, hereinafter described, cutting through the insulation of a wire and in position to firmly grasp the conductor.

Referring to the embodiment of my invention shown in the drawings, the binding post comprises a cap 1, a plunger 2 and a base member 3. The cap 1 comprises an internally threaded hollow cylindrical chamber open at one end and provided with a flange 14, the closed end being pierced by an axial aperture 4.

The plunger 2, designed to slidably move longitudinally within the base member 3, is positionable by the cap 1. The said plunger comprises a forked member 5, at the upper end of

2

which is a shaft 6 terminated by a flange 7. The forked member 5 comprises fingers 8, 8, the lower ends of which terminate in cutting edges 9, 9. The external faces of the fingers 8, 8 taper from their upper ends to the cutting edges 9, 9, and are provided with two pressure shoulders 21, two limiting shoulders 22 and with two bevel points 16. The internal faces of the fingers are substantially parallel.

5 The base member 3 comprises an upper member 10, a base plate 11 and an attachment member 12 symmetrically arranged about a common axis. The upper member 10 comprises an axially bored cylinder, the internal diameter of which is slightly greater than the greatest diameter of the plunger 2. The upper member 10 is provided with a screw thread 13, threadably engaged with the cap 1 aforesaid. The lower part 15 of the upper member 10 bears a right angle slot 15 comprising a horizontal cut and a vertical cut, which vertical cut includes the lower portion of the bore of the upper member 10.

20 The upper member 10 is equipped with a guide pin 17. This guide pin is located near the top 25 of the upper member 10, and transverses the center of this member parallel to the transverse axis of the vertical leg of slot 15. Located below guide pin 17 are pressure pins 18, 18. These pressure pins are parallel to pin 17 and transverse the interior of upper member 10 close to its interior walls.

25 Base plate 11 is positioned between the upper member 10 and the attachment member 12. The base plate 11 is provided with an axial bore 19, 30 which bore 19 is continued into the attachment member 12. The diameter of the bore 19 is less than the interior diameter of upper member 10, and is slightly greater than the exterior diameter of fingers 8, 8 at their cutting edges 9, 9. The base plate 11 is provided with beveled surface 35 20 to cooperate with the two bevel points 16 to facilitate admission of cutting edges 9, 9 into the bore 19 and to aid in forcing the fingers 8, 8 together after the said cutting edges 9, 9 have 40 penetrated the insulation of the wire.

45 To assemble this embodiment of my invention, the shaft 6 is inserted through the axial aperture 4 and the flange 7 is then turned down. The cap 1 is then coupled to the base member 50 3 and the flange 14 is turned down. Thus in assembly the longitudinal position of the plunger 2 in the base member 3 is determined by the position of the cap 1. The axial alignment of the plunger 2 is fixed by guide pin 17, the diameter of which pin is slightly less than the

horizontal dimension between the parallel interior faces of fingers 8, 8.

In operation, the cap 1 is raised to its greatest height on the base member 3, thus raising the plunger 2 to a point above the slot 15, in the base member 3. A wire to be attached to the binding post is then introduced through slot 15 and placed in the lower part of the vertical leg. The cap 1 is then screwed downward, forcing the cutting edges 9, 9 through the insulation of the wire, as is illustrated in Figure 4. Due to the position of the guide pin 17, the cutting edges 9, 9 strike the wire parallel to the axis of the wire. At this point, the insulation from the wire has been displaced and the fingers 8, 8 are in electrical contact with the conductor of the wire. As the plunger is further forced downward, the pressure pins 18, 18 engage a greater dimension of the plunger and force the fingers of the plunger together. Thus the two pressure shoulders 21, are so located that they engage the pressure pins 18, 18 as the cutting points 9, 9 enter the bore 19. This action results in the fingers tightly gripping the conductor; thus, when the cap is at its lowermost position, the cutting edges 9, 9 have penetrated through the insulation of the wire and have firmly grasped the conductors. The lower parts of the fingers extend into the bore 19, thus aiding the pressure exerted against the fingers by the pressure pins 18, 18.

My invention thus discloses a simple and convenient means whereby an insulated conductor may be attached to a binding post. A permanent lead-in wire may be attached to the post in any convenient manner. Since the electrical circuit is through the base member to the plunger, these parts must be made of electrical conductive material. The cap may be made of any convenient material, whether conductive or not.

Although one embodiment of this invention has been shown it is realized that many modifications and changes in this invention are possible. It is realized, for instance, that instead of the pins 18, 18 coacting with beveled areas on the fingers, that the downward movement of the cap might be utilized to force inwardly moveable parts on the base member that at the proper time would exert a closing pressure on the fingers. It is also realized that other means than guide pin 17 might be utilized to guide the plunger 2. It is therefore intended in the appended claims to cover all such modifications and changes as lie within the spirit of this invention.

I claim:

1. A binding post for piercing the insulation on a wire and gripping the conductor therein, comprising an electrical conducting base member having an axial aperture for the admission of a cutting and gripping member and a lateral orifice for the admission of a wire opening to said axial aperture, a cutting and gripping member comprising an elongated electrical conducting member having two longitudinally disposed fingers coaxially disposed within said base member, said fingers being beveled on their external faces, substantially parallel on their internal faces and bearing cutting edges on their extreme ends, a cap member threadably coupled to said base member and adapted to move said cutting and gripping member longitudinally within said base member along the axial aperture, and means within said base member to cooperate with said beveled edges on said fingers to force said fingers together for gripping the conductor of the wire.

after said cutting edges have been forced through the insulation of the wire, said base member and said cutting and gripping member being in electrical contact with each other.

2. In a binding post for an insulated conductor, the combination with an electrically conductive partially hollow base member formed with an aperture, said aperture being formed at least in part by bearing surfaces and a lateral slot leading to said aperture for the admission of said insulated conductor, of an electrically conducting cutting and gripping member comprising two fingers integrally connected at the upper ends and having cutting edges at the lower ends, the internal faces of said fingers being disposed substantially parallel to each other and the external faces of said fingers being inwardly tapered from the upper end to the cutting edge, means for longitudinally displacing said cutting and gripping member towards and into said aperture in said electrically conducting base member, said bearing surfaces and external faces coming into camming engagement at a predetermined point of said longitudinal displacement so that when said insulated conductor is positioned in said slot proximate to and in the path of said cutting edges, substantially transversely of said fingers and substantially parallel to said internal faces, upon longitudinal displacement of said cutting and gripping member, said cutting edges penetrate the insulation on opposite sides of said conductor and said fingers straddle said conductor and, upon operation of said camming engagement, said fingers are moved inwardly to grip said conductor and make electrical contact therewith.

3. In a binding post for an insulated conductor formed with an aperture, said aperture being formed at least in part by bearing surfaces, an electrically conducting cutting and gripping member comprising two fingers integrally connected at the upper ends and having cutting edges at the lower ends, the internal faces of said fingers being disposed substantially parallel to each other and the external faces of said fingers being inwardly tapered from their upper ends to their cutting edges, said cutting and gripping member having a longitudinal operable movement towards and into said aperture, said external faces coming into camming engagement with said bearing surfaces to urge said fingers toward each other during the latter portion of said longitudinal movement so that when said insulated conductor is positioned proximate to and in the path of said cutting edges, substantially transversely of said fingers and substantially parallel to said internal faces, upon longitudinal operable movement of said cutting and gripping member, said cutting edges penetrate the insulation on opposite sides of said conductor and said fingers straddle said conductor and, upon operation of said camming engagement, said fingers are moved inwardly to grip said conductor and make electrical contact therewith.

4. A binding post for a cable made up of a conductor with insulation thereon, comprising a base member formed with an aperture, said aperture being formed at least in part by cam surfaces, a plunger having an operable movement relative to said base member and including two substantially parallel fingers which are spaced apart substantially the width of said conductor, said fingers having edges for cutting insulation on their extremities and cam follower surfaces on their outer faces, said cam follower surfaces being engageable with said cam surfaces on the

base member during the latter portion of said operable movement of the plunger so as to urge the extremities of said fingers toward each other, and means to operably move said plunger, so that a cable may be operably positioned relative to said plunger and during the operable movement of said plunger, the said fingers first cut through the insulation and straddle the conductor and are then urged inwardly to grip said conductor and make good electrical contact therewith.
